UNITED STATES PATENT OFFICE.

ROBERT SCHILLER, OF CHICAGO, ILLINOIS.

WINDOW-WASHER'S SEAT.

Application filed September 16, 1921. Serial No. 501,089.

To all whom it may concern:

Be it known that I, ROBERT SCHILLER, a citizen of the United States, and a resident of Chicago, in the county of Cook and State 5 of Illinois, have invented certain new and useful Improvements in Window-Washers' Seats, of which the following is a full, clear, and exact description.

My invention relates to a seat structure to 10 be applied on the sills of windows to support persons while washing the outside of the windows.

One of the important objects of my invention is to provide a simple, practical and 15 efficient structure which is adjustable to accommodate itself to windows of different types and dimensions. Another important object is to provide a structure which can be folded into small space when not in use. 20 Another object is to make the structure light so that it can be readily carried, but at the same time to make it strong and safe.

The above and other features of my invention are incorporated in the structure 25 shown on the accompanying drawing, in which—

Fig. 1 is a perspective view of my improved seat structure in unfolded position ready for application to a window sill and 30 ledge,

Fig. 2 shows the device folded up,

Fig. 3 is a side elevational view showing the structure in place ready for use,

Fig. 4 is a plan view of the structure 35 shown in Fig. 3, and

Fig. 5 is a fragmentary view showing a modified arrangement.

The device comprises a back 10 which may be of sheet metal and reenforced along its 40 side edges by angle bars 11. Hinged to the back by hinges 12 and near the lower edge of the back is the seat board 13 which may also be of sheet metal suitably reenforced along its side edges by angle bars 14.

45 Hinged to the back 10 near the upper corners thereof by hinges 15 are the side structures 16 and 17 in the form of "lazy-tongs" frames built up of the bars 18 pivoted together. Each frame is secured by its rear

50 bar 18^a to the hinge 15, the sides being thus extensible longitudinally. The front bar 18^b of each side frame terminates at its lower end in a hook 19.

In Fig. 3 I show the device applied to a 55 window structure. The hooks 19 are engaged around the inner edge of the inner

sill board 20 and the seat board 13 rests against the top of the ledge 21. If the ledge together with the sill are of sufficient width to accommodate a sitting person then 60 the end 10' of the back below the seat board is brought up against the outer edge of the ledge. After application to the sill board and ledge the seat and back are rigidly locked in open relationship by the strut bars 65 22 and 23 hinged to the respective angle bars 14 on the seat frame and receiving the pins or buttons 24 on the back angle bars 11, a row of slots 25 being provided in each strut bar to provide for adjustment. Also 70 after application of the seat the lazy-tongs side frames are rigidly locked against expansion or contraction by means of the lock bars 26 which are pivoted at the upper ends of the respective rear bars 18^a of the frame 75 and at their outer ends have the notches 27 for receiving button heads 28 provided on the pivot pins which connect together the frame bars intermediate their ends. The seat structure is now rigidly held to the 80 window structure and a person can comfortably sit on the seat board and supported by the back 10, be in convenient position for washing the windows on the outside.

If the sill board and ledge board do not 85 afford sufficient width for comfortable sitting, then the seat board is shifted outwardly as indicated in dotted lines in Fig. 3 to bring the back away from the outer edge of the ledge. The strut bars 22 and 90 23 and the lock bars 26 are then applied to rigidly lock the structure against collapse. The structure is thus readily extensible and adjustable for different widths of window structures and when the brace 95 bars and locking bars are applied the structure is strong and rigid and can be used with comfort and safety.

When the device is not in use the seat board is folded up against the back board 100 and the lazy-tongs frames are contracted and swung inwardly against the seat and back board as indicated in Fig. 2. The strut bars are swung into a position parallel with the angle bars 14 and the lock bars 105 26 will hang down in front of and parallel with the seat board. When the device is thus folded up it is very compact and occupies little space and can be easily transported, packed, and shipped.

In Fig. 5 I have shown a modified arrangement for locking the lazy-tongs

- frames. Instead of providing slots in the lock bars 29 I provide a single longitudinal slot 30 which receives the pivot pins 31 of the frame bars, these pins being threaded at their outer ends to receive the wing nuts 32. After setting of the device in place the wing nuts are screwed down to rigidly clamp the locking bars and thus lock the frame against expansion or contraction.
- 10 I do not desire to be restricted to the details set forth, as these may be modified within the scope of the appended claims, without departing from the spirit and scope of the invention.
- 15 I claim as my invention:
1. In a window washer's seat, the combination of a back, means for supporting said back on a window ledge, lazy-tongs structures extending forwardly from said back and means for detachably securing the ends of said structures to a window sill.
  2. In a window washer's seat, the combination of a back, means for supporting said back on a window ledge, lazy-tongs structures extending forwardly from said back, means for securing the ends of said structures to a window sill, and means for locking the structures in more or less extended positions.
  3. A detachable seat structure for window frames comprising a back, side arm structures in the form of lazy-tongs extending forwardly from said back, means for supporting said back on the ledge of the window frame, and hooks at the front ends of said side structures for engaging around the inner edge of the window sill.
  4. In a window frame seat attachment, the combination of a back, means for supporting said back on the outer edge of a window frame, longitudinally foldable side arm structures extending forwardly from said back, means at the outer ends of said arms for engaging with the inner sill board of the window frame, said arms being hinged to said back whereby when folded up they may be swung against said back.
  5. In a seat attachment for window frames, the combination of a back, means on said back for supporting it on the outer ledge of the window frame, side arm structures extending forwardly from said back, hooks at the front ends of said side arm structures for engaging around the inner edge of the inner sill board, said side arm structures being foldable longitudinally and hinged to said back whereby after folding they may be swung against said back.
  6. In a seat attachment for window frames, the combination of a back, means at the lower end of said back for supporting it on the outer ledge of a frame, side arm structures in the form of lazy-tongs extending from said back, means at the outer ends of said side arm structures for securing them to the inner sill board of the frame, locking mechanism for locking said lazy-tongs in expanded position, said lazy-tongs being hinged to said back whereby when they are folded up longitudinally they may be swung against the back.
  7. In a window washing detachable seat for window frames, the combination of a back, a seat board hinged to said back near the lower edge thereof and adapted to be folded against said back, strut bars for holding said seat in fixed position away from said back, said seat being adapted to rest on the ledge of a window frame, adjustable side arm structures extending from said back, means at the outer ends of said side arm structures for engaging with the inner window sill of the frame, said side arm structures being hinged to the back to be folded against the back when the device is not in use.
  8. In a window washing seat attachment for window frames, the combination of a back, a seat board hinged to said back near the lower edge thereof, said seat board engaging with the ledge of a window frame, strut bars engaging with said back and seat for holding said back in upright position, side arm structures extending forwardly from said back, hooks at the front ends of said side arm structures for engaging around the inner edge of the inner sill board of the frame, said side arm structures being foldable longitudinally and being hinged to said back board to be swung against the back board when folded, said seat board being adapted to be swung against said back.
  9. In a window washing attachment for window frames, the combination of a back, a seat board hinged to said back near the lower edge thereof for resting on the ledge of a window frame, strut bars hinged to said seat board and having adjustable engagement with said back for holding said back in upright position, side arm structures in the form of lazy-tongs hinged to said back, hooks at the front ends of said side arm structures for engaging around the inner edge of the inner sill board of the frame, said seat board when released by said strut bars being foldable against said back, and said side arm structures when folded longitudinally being adapted by their hinge connection to be swung against said back.
  10. In a window washing detachable seat structure for window frames, the combination of a back board and a seat board hinged together, means for locking said boards in open position with said seat board resting on the ledge of a window frame and the back board held in upright position, side arm structures in the form of lazy-tongs hinged to said back board, hooks at the front ends of said side arm structures for engaging around the inner edge of the inner sill board of the frame.

of the window frame, and lock bars for locking said side arm structures in extended position, said structures when released from said locking bars being foldable longitudinally and being adapted to be swung against the back board by virtue of their hinge connection therewith.

11. In a detachable seat structure for window frames, the combination of a back, means for supporting said back in upright position on a window ledge, side arm structures in the form of lazy-tongs extending from said back, means at the front ends of said side arm structures for securing them to the inner sill board of a window frame, and locking bars adapted to engage with the bars of the lazy-tongs frames to prevent relative movement thereof whereby said

frames when expanded are locked against contraction.

12. In a detachable seat for window frames, the combination of a back, means for supporting said back at the outer edge of the ledge of a window frame, lazy-tongs extending from said back near the sides thereof, hooks at the front ends of said lazy-tongs for engaging around the inner edge of the inner sill board of the frame, and means for locking the bars of said lazy-tongs frames against relative movement to thereby rigidly lock said frame.

In witness whereof, I hereunto subscribe my name this 9th day of September A. D., 1921.

ROBERT SCHILLER.
